Primary Examiner — David G Muller*Assistant Examiner* — Christina Gabrielle Cosden*(74) Attorney, Agent, or Firm* — Merchant & Gould P.C.(57) **CLAIM**

The ornamental design for an electronic deadbolt for door as shown and described.

DESCRIPTION

FIG. 1 is a top perspective view of an exemplary electronic deadbolt for a door according to a new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and

FIG. 8 is a bottom perspective view thereof.

FIG. 9 is a top perspective view of another exemplary electronic deadbolt for a door according to a new design;

FIG. 10 is a front view thereof;

FIG. 11 is a back view thereof;

FIG. 12 is a left side view thereof;

FIG. 13 is a right side view thereof;

FIG. 14 is a top view thereof;

FIG. 15 is a bottom view thereof; and,

FIG. 16 is a bottom perspective view thereof.

The portions depicted in broken lines form no part of the claimed design.
